BEDPAN

Filed May 17, 1923

UNITED STATES PATENT OFFICE.

ANNIE N. MABRY, OF NEW YORK, N. Y.

BEDPAN.

Application filed May 17, 1923. Serial No. 639,612.

To all whom it may concern:

Be it known that I, ANNIE N. MABRY, citizen of the United States, and resident of New York, in the county of New York and State of New York, have invented certain new and useful Improvement in Bedpans, of which the following is a specification.

This invention relates to sick bed utensils in general and particularly to bed pans.

10 The prime object of this invention is to provide a bed pan of novel construction provided with means for flushing it.

Another object of this invention is to provide means for controlling the flushing operation in my device.

In order to better bring forth the advantages of my invention a brief comparison between the existing types of bed pans and my devices and its use will be in place.

20 Heretofore receptacles for the use of patients confined to bed could be used, in most cases, only when the attendant was present, since the emptying or cleansing of the used receptacle could be only done by such attendant.

At night times or at times when the attendant would not be at the bedside of the patient the latter was subjected to a great discomfort due to the absence of the attendant, or when the receptacle was put in place before the attendant left and after the patient had used the pan and was forced to lie above the used pan before same was emptied by the attendant.

30 My invention eliminates all the discomforts to which the patient is subjected by such delays, as he himself can readily cleanse the receptacle without the help of the attendant, by simply actuating a hand operating device at the side of the pan.

The foregoing objects and comparisons will be more fully understood from the following description and the accompanying drawings forming part of this specification, and in which:

Figure 1 represents one of the many preferred forms of my device in connection with a receiving receptacle for the refuse.

Figure 2 is an enlarged cross-sectional view taken on line 2-2 of Figure 1.

50 Figure 3 is a cross-sectional view taken on line 3-3 of Figure 1.

Referring to the drawings numeral 10 denotes an open receptacle of any suitable 55 shape provided with a peripheral flange 11 and having an outlet indicated at 12. The

bottom of the receptacle may be either funnel-shaped or similarly formed as shown in Figure 3.

Superimposed above the flange 11 there is a fluid container or receiver 13 provided at its inner wall with a plurality of apertures indicated at 14.

The receptacle 10 and container 13 may be made of any suitable material and the top may be covered with cloth, fibre, wood rubber or any other material not shown in the drawings.

At the outer wall and preferably at the shorter side of the receptacle, there is provided a closable neck 15 through which water or a disinfectant may be readily passed into the fluid receiver.

Circumscribing the inner face of the inner wall of the receiver and normally pressing against the apertures 14 is a band-like member 16 of either rubber, impregnated fabric or leather, which is held in its position adjacent to that inner wall and against apertures 14 by means of a spring device, 80 indicated at 17, which latter is operable from without through handle 18.

This spring device 17 is water-tightly associated with the outer wall of the container, so as to preclude any leakage at this point.

Apertures 14 facing the open receptacle 10 are preferably arranged in near proximity to the upper edge of the receptacle 10. Attached to aperture 12 is a hose or pipe 90 19, the free end of which is adapted to be inserted in a portable container, indicated at 20.

Before use of the bed pan, the container is filled through neck 15 with either water or disinfectant fluid, and is placed into the bed of a patient while the hose 19 is inserted in the portable container 20.

After having used the receptacle for its intended purpose, a patient or the attendant may press handle 18 whereby band 16 is spread or loosened from its tightening hold upon the inner wall of the container, whereby apertures 14 are freed and permit the fluid from the container to flush the receptacle 10.

This operation causes the refuse to flow through hose 19 into the portable receiver 20, which may be emptied at any time after the use of the bed pan.

110 While I have shown a specific construction of my device and mentioned the use

thereof for patients in sick-beds only, be it understood that its construction shape and use may be varied, as it may be readily applied for douching or any other purpose, and I therefore reserve for myself the right to make changes and improvements within the broad scope of my invention, for which I claim:

1. A flushable bed pan having a fluid reservoir provided with perforations facing the pan proper, means normally closing the perforations and operating means for releasing said closing means at will.
2. A flushable bed pan comprising an open receptacle, a fluid reservoir superimposed above the former and provided with apertures facing said receptacle, closing means for said apertures, and operating means for releasing said closing means at will.
3. A flushable bed pan comprising an open receptacle, a fluid container superimposed above the former and provided with

a plurality of apertures facing said receptacle, a band within said container normally pressing against said apertures, operating means for said band adapted to spread the latter for freeing said apertures of the container to permit the fluid stored therein to issue into said receptacle.

4. A flushable bed pan, comprising an open receptacle provided with an outlet, a fluid container arranged above said receptacle and provided with perforations at its inner wall facing said receptacle and a closable neck for filling the container, a peripheral band arranged within said container and adapted to normally close the said perforations, operating means extending outwards from said container and adapted to spread said band when fluid is to be allowed to pass into said receptacle.

Signed at New York, in the county of New York and State of New York, this 15th day of May, A. D. 1923.

ANNIE N. MABRY
